(57) **CLAIM**

I claim the ornamental design for a sliding interdental brush, as shown and described.

DESCRIPTION

FIG. 1 is a perspective view of the sliding interdental brush showing my new design;

FIG. 2 is a front view of the sliding interdental brush;

FIG. 3 is a rear view of the sliding interdental brush;

FIG. 4 is a right side view of the sliding interdental brush; and,

FIG. 5 is a top view of the sliding interdental brush. The broken lines showing the brush head, the brief surface within the handle and immediately below the button, and the elements within the handle near its distal end illustrate portions of the sliding interdental brush that form no part of the claimed design.
